UNITED STATES PATENT OFFICE.

WILLIAM SCHWEMLEIN, OF PARKERSBURG, WEST VIRGINIA, ASSIGNOR TO THE PARKERSBURG RIG & REEL COMPANY, OF PARKERSBURG, WEST VIRGINIA, A CORPORATION OF WEST VIRGINIA.

COUNTERBALANCED BAND WHEEL.

Application filed July 1, 1927. Serial No. 202,953.

This invention relates to band wheels for oil well apparatus designed and adapted for pumping and for other operations and more particularly to readily adjustable counter-balances for the band wheels employed in such apparatus.

The principal object of this invention is to provide a counter-balanced band wheel having counter-weights which may be easily and quickly moved into operative position to balance the sucker rod secured at the end of the beam over the well when the apparatus is used for pumping, and into an inoperative or neutral position when the apparatus is used to perform other operations than pumping.

A further object of this invention is to provide a band wheel having a plurality of counter-weights pivotally mounted on a support carried by a portion of the hub of the band wheel which may be quickly and securely held or locked in operative or in inoperative or neutral position and which may be readily shifted from one of such positions to the other and readily secured in such position.

Other objects and advantages will become apparent during the course of the following description.

As will be readily understood by those skilled in the art, it is desirable to provide the band wheels employed in oil well apparatus for pumping and drilling and the like, with means for counter-balancing the sucker rod carried on the end of the walking beam and operated by the band wheel. Moreover since the rig is employed for purposes other than pumping, it is desirable that the counter-balances may be readily shifted into a neutral or inoperative position when it is not necessary to provide a counter-balance for the sucker rod. Various types of counter-balances for band wheels have been provided heretofore but such counter-balances have not been found to be wholly satisfactory because of the lack of ease with which the counter-weights are shifted back and forth between the operative and inoperative or neutral positions. By the employment of this invention the band wheel counter-weights may be readily securely held or locked in either operative or neutral position and may be readily shifted to the opposite position and quickly secured therein.

In the accompanying drawings I have

shown a preferred embodiment of my invention. In this showing:

Figure 1 is a side elevation with the counter-weights in operative position,

Figure 2 is a side elevation with the counter-weights in neutral position, and,

Figure 3 is a detail perspective view of one of the counter-weights.

Referring to the accompanying drawings the numeral 10 designates a band wheel of conventional construction. The band wheel is provided with a hub portion 11 having a boss 11' to which is secured a supporting arm 12 spaced from the face of the band wheel and provided with a longitudinally extending web 13 arranged between the arm 12 and the face of the band wheel 10. The boss 11' is provided with a central opening which is adapted to receive a drive shaft 14 to which the band wheel is keyed by means of a key or spline 15.

A pair of counter-weights 16 are pivotally mounted on pins 17 carried by the arm 12. Each of the counter-weights is preferably in the form of a skeleton sector and is provided with a heavily weighted portion 18 adjacent the outer end thereof. A T-shaped abutment 19 is arranged on the band wheel 10 adjacent the periphery thereof and the weighted portions 18 are cut away as at 20 and 21 to receive such abutment. The inner portion 22 of each of the counter-weights is provided with an opening 23 adapted to receive the pins 17 carried by the arm 12. The counter-weights 16 are provided with gear teeth 24 which are adapted to intermesh regardless of the position of the counter-weights. The inner portion 22 and the weighted outer portion 18 of each of the counter-weights are connected by spaced connecting arms 25 and 28. The arms 25 are provided with a plurality of spaced openings 26 and are designed to lie in abutting relation when the counter-weights are in their outer or operative position. The arms 25 are adapted to be secured together by means of nuts and bolts 27, the openings 26 in each of the members 25 being in alined position when the counter weights are in operative position to receive bolts therethrough. The connecting arms 28 are curved as at 29 and the weighted portions 18 are cut away as at 30 in order to receive the boss 11' when the counter-weights are in

the neutral position.

neutral position. Each of the weighted members is also cut away as at 31 to receive a lip 32 carried by the other of the weighted portions. The lips 32 are arranged to overlap when the counter-weights are in neutral position and are provided with openings 33 which are adapted to receive a bolt 34 to secure the counter-weights in inoperative position.

5 In the operation of the device when the band wheel is being used in pumping operations the counter-weights 16 are swung into operative position as indicated in Figure 1, and the members 25 are secured together by means of the nuts and bolts 27. It will be readily apparent that when the members 16 are in this position they will serve as a counter-balance for sucker rods or the like. When it is desired to operate the band wheel without 10 a counter-balance the counter-weights 16 are moved into neutral position by removing the nuts and bolts 27 and swinging the members 16 into inoperative or neutral position as indicated in Figure 2. The lips 32 are then 15 secured together by means of a bolt 32 arranged in the openings 33.

It will be understood that the support 12 is of such length with respect to the counter-weight 16 that the weighted members 18 will 20 lie adjacent the edge of the band wheel 10 when they are in operative position and will lie adjacent the geometrical center of the wheel 10 when in neutral position. The gear teeth 24 are provided on the weights so that 25 if the counter-weights are positioned horizontally the two members will balance one another when the shift from the operative to the inoperative position or vice versa is made.

30 40 While I have described in detail the preferred embodiment of my invention it is to be understood that the shape, size and arrangement of parts may be widely varied without departing from the spirit of the invention or the scope of the subjoined claims.

I claim:

1. A device of the character described comprising a rotatable member, a supporting arm carried by and spaced from said member, 45 counter-balancing means pivotally mounted on said supporting arm, said counter-balancing means being adapted to swing in a plane parallel to the plane of said rotatable member, and means for securing said counter-balancing means in operative or counter-balancing and inoperative or neutral positions.

2. A device of the character described comprising a rotatable member having a hub portion, a supporting arm carried by said hub 50 portion, a plurality of counter-weights pivotally mounted on said supporting arm, and

means for securing said counter-weights in operative or counter-balancing and inoperative or neutral positions.

3. A device of the character described comprising a band wheel, a supporting arm carried by said band wheel, a pair of counter-weights pivotally mounted at their inner ends on said supporting arm, said counter-weights having weighted portions at the outer ends 65 thereof, and means for securing said counter-weights in operative or counter-balancing and inoperative or neutral positions.

4. A device of the character described comprising a band wheel, a supporting arm carried by said band wheel, a pair of counter-weights pivotally mounted at their inner ends on said supporting arm, said counter-weights having weighted portions at the outer ends 70 thereof, and means for securing said counter-weights in operative or counter-balancing and inoperative or neutral positions, the inner ends of said counter-weights being provided 75 with intermeshing gear teeth.

5. A band wheel having a central hub portion, a supporting arm carried by said hub portion, counter-weights hingedly mounted on said supporting arm intermediate the hub portion and the periphery of said band wheel, an abutment carried by said band wheel adjacent the periphery thereof, and means for detachably securing said counter-weights in 80 operative position in abutting relation with said abutment.

6. A band wheel having a central hub portion provided with a projecting boss, counter-weights indirectly carried by said band wheel and pivotally mounted intermediate said hub portion and the periphery of said band wheel, the outer portion of said counter-weights being cut away at a point removed 85 from their pivot points to receive said boss when the counter-weights are in inoperative position, and means for detachably securing said counter-weights in inoperative position. 90

7. A band wheel having a central hub portion provided with a projecting boss, counter-weights indirectly carried by said band wheel and pivotally mounted intermediate 95 said hub portion and the periphery of said band wheel, the outer portion of said counter-weights being cut away at a point removed from their pivot points to receive said boss when the counter-weights are in inoperative position, and over-lapping ears carried by the 100 outer portion of said counter-weights, said ears being adapted to be detachably secured together to hold the counter-weights in inoperative position.

In testimony whereof I affix my signature.

WILLIAM SCHWEMLEIN.
